DESK

Irving Kramer, White Plains, N. Y.

Application December 7, 1948, Serial No. 150,031

Term of patent 7 years

(Cl. D33—7)

To all whom it may concern:

Be it known that I, Irving Kramer, a citizen of the United States of America, residing at 9 Bursley Place, White Plains, New York, have invented a new, original, and ornamental Design for Desk, of which the following is a specification, reference being had to the accompanying drawing, forming part thereof.

Fig. 1 is a front perspective view of a desk with the extension leaf in its raised position showing my new design; and

Fig. 2 is a rear perspective view thereof with the extension leaf shown in its lowered position.

I claim:

The ornamental design for a desk, as shown.
IRVING KRAMER.
